UNITED STATES PATENT OFFICE.

WILLIAM E. BROCK, OF DUNELLEN, NEW JERSEY.

HAMMOCK-SPREADER.

SPECIFICATION forming part of Letters Patent No. 325,048, dated August 25, 1835.

Application filed September 21, 1834. (No model.)

To all whom it may concern:

Be it known that I, WILLIAM E. BROCK, of Dunellen, in the county of Middlesex and State of New Jersey, have invented a new and useful Improvement in Hammock-Spreaders, which has not, to my knowledge, been patented in any country, and of which the following is a full, clear, and exact description, reference being had to the accompanying drawings, which form a part of this specification.

This invention relates to an improvement in hammock-spreaders or devices for distending a hammock laterally while suspended; and the object of the invention is to provide a strong and durable hammock-spreader which can be very readily placed in position for use, and will keep the suspension-cords firmly in position without any possibility of their lateral displacement, said suspension-cords being separately passed through the spreader about midway at intervals along its entire length, so as to have a solid thickness of wood both below and above them.

The invention consists, as to its main feature, in a hammock-spreader composed of two curved bars placed vertically the one above the other, the upper bar having slots on its under side to receive the suspension-cords, and said bars being hinged or pivoted at one end to admit of their being separated to receive the said cords and provided with a suitable clasp at their other end for fastening them together after the hammock has been placed thereon; and the said invention further consists in certain novel constructions and combinations of parts, all as hereinafter particularly described.

In the accompanying drawings, Figure 1 represents a perspective view of a hammock with my improvement; Fig. 2, a side view of the spreader detached from the hammock; Fig. 3, a side view of a pivot or hinge of novel construction forming part of my improvement. Fig. 4 is an end view of said pivot or hinge. Figs. 5 and 6 are similar views of the clasp, and Fig. 7 is a modification hereinafter explained.

Similar letters of reference indicate the same parts in all the several figures.

A may represent a hammock of ordinary construction, suspended by means of cords *a*, which are brought together in a ring or loop, *b*, in the usual manner.

B represents my improved hammock-spreader, one of which I ordinarily apply to each end of the hammock to expand the same laterally when suspended. The said spreader is composed of two parallel curved bars, *c* and *d*, placed vertically over each other. The lower bar, *c*, is a solid strip of wood, (or other suitable material,) and the upper bar, *d*, (also of wood or other suitable material,) is provided with slots *e e e*, &c., adapted to receive the suspension-cords *a*, each of which passes through and is held in position by its respective slot. The two bars are similarly curved, so as to fit to each other when brought together, the lower bar, *c*, covering the bottoms of the slots *e* in the upper bar. The said bars are hinged or pivoted together at one end by means of a suitable hinge or pivot, *C*. This may be of any suitable construction; but I prefer to make it in the form shown. My said hinge or pivot is made from a short length of wire, which is first passed through the lower bar, *c*, then bent upward and passed through the upper bar, *d*, and then bent downward and twisted over the projecting end *f* of the portion which passes through the lower bar, *c*. A small staple, *g*, embraces one side of the link thus formed, and is driven into the upper bar, as shown. The end of the upper bar is slightly beveled, as at *h*, so as to allow the lower bar to turn on the pivot and be separated from the upper bar, as shown by dotted lines in Fig. 2, to permit the suspension-cords being inserted into the slots *e*. By means of this construction the bars may be separated the desired distance, and are prevented from being further separated by reason of the end of the bar *c* resting against the bevel *h* on the end of the upper bar.

After the several suspension-cords have been inserted into their respective slots, the two bars are brought together and fastened by means of the clasp *D*. This clasp may be of any suitable form; but I have shown a clasp of novel and inexpensive construction which is specially adapted to be used in connection with my improved spreader. This clasp is made in the form of a loop, pivoted at its base in the lower bar, *c*, and its looped end adapted to pass over a shoulder, *i*, on the end of the upper bar, *d*, and fit into and rest in a groove, *k*, in the end of said bar *d*. It is formed from a short length of wire bent to fit snugly to the sides of the

bars and to pass loosely over the shoulder *i* and fit into the groove *k*. One end of the wire passes through the bar *c*, forming a pivot and the base of the loop, and the opposite end of the wire (after forming the loop) is twisted over the projecting end *l* of the portion forming the base or pivot of the loop.

From the above description of my improved spreader it will be obvious that thus constructed it is very strong, firm, and durable, that the suspension-cords are prevented from moving sidewise, and that the spreader can be very easily and quickly applied to the hammock or disengaged therefrom at pleasure.

15 In the modification shown in Fig. 7 the only difference is, that the slots *e* are made to slant from the ends toward the center of the spreader, with a view to the more easy insertion of the suspension-cords, and to retain each within 20 its slot while they are being successively inserted and until the two bars are clasped together.

What I claim as my invention is—

1. A hammock-spreader composed of two

parallel curved bars placed vertically the one 25 over the other, the upper bar having slots on its under side to receive the suspension-cords, and said bars being hinged together at one end to admit of their being spread apart, and provided with a suitable clasp at their other end 30 for connecting them together after the hammock has been placed thereon, as set forth.

2. In combination with the lower solid bar, *c*, and upper slotted bar, *d*, provided with the bevel *h*, the hinge or pivot *C*, constructed as 35 described, for the purpose set forth.

3. In combination with the lower bar, *c*, and upper bar, *d*, provided with the groove *k* and shoulder *i*, the clasp *D*, constructed as described, for the purpose set forth. 40

4. In a hammock-spreader, the combination of an upper slotted bar, *d*, a lower solid bar, *c*, and a pivot-hinge, *C*, and clasp *D*, both constructed as described, for the purpose set forth.

WILLIAM E. BROCK.

M. H. TOPPING.

Correction in Letters Patent No. 325,048.

It is hereby certified that Letters Patent No. 325,048, granted August 25, 1885, upon the application of William E. Brock, of Dunellen, New Jersey, for an improvement in "Hammock-Spreaders," should have been issued to Hamilton F. Disbrow, of Brooklyn, and Herman G. Disbrow, of New York, New York, as assignees of the said William E. Brock; that this correction has been made in the files and records of the case in the Patent Office, and should be read in the Letters Patent that the same may conform thereto.

Signed, countersigned, and sealed this 1st day of September, A. D. 1885.
